CLAIM

The ornamental design for a storage module for microcomputer equipment, substantially as shown and described.

DESCRIPTION

FIG. 1 is a front elevational view of a storage module for microcomputer equipment showing my new design;
FIG. 2 is a top plan view thereof;
FIG. 3 is a rear elevational view thereof;
FIG. 4 is a bottom plan view thereof; and
FIG. 5 is a left side elevational view, the right side being a mirror image thereof.

FIG. 1

FIG. 2
